ATTORNEY

UNITED STATES PATENT OFFICE.

WILLIAM HANDLER, OF JERSEYVILLE, ILLINOIS.

HEAT-DISTRIBUTING PLATE.

Application filed June 28, 1923. Serial No. 648,326.

To all whom it may concern:

Be it known that I, WILLIAM HANDLER, a citizen of the United States, residing at Jerseyville, in the county of Jersey and State of Illinois, have invented a new and useful Heat-Distributing Plate, of which the following is a specification.

This invention relates to a plate, which is adapted to be used for distributing heat from the flame of an oil stove, or other source of heat, so that the same may be utilized in cleaning oil stove chimneys, whereby the latter will operate without smoking.

Many attempts have been made to devise an oil stove burner and chimney, which may be used without the formation of smoke or offensive odors, but nevertheless in all such constructions after the stove has been used for a time heavy oils, carbon, grease, and other by-products of petroleum accumulate in the lower part of the chimney below the edge of the flame, where they are not subject to intensified heat, and are therefore heated only enough to cause the formation of offensive vapor or smoke.

It is the object of the present invention to provide a device which will be simple and inexpensive and may conveniently be used to facilitate the removal of such accumulations on the chimney, so that the same will operate as efficiently as that of a new stove. By using my invention from time to time for the purpose stated, the oil stove will always be in a condition to work satisfactorily.

The structure of my invention and the principles embodied therein will best be understood from the following detailed description taken in connection with the accompanying drawing, which illustrates the invention in its preferred form, and the method of using the same.

In the drawing:

Figure 1 is a perspective view of a three-burner oil stove, with my invention being used thereon.

Figure 2 is a detail view, partly in section, of the chimney being cleaned.

Figure 3 is an enlarged plan view of my invention with portions broken away to illustrate the several layers thereof.

Figure 4 is a vertical section on the line 4-4 of Figure 3.

The oil stove 5, illustrated in Figure 1, has three burners 6, 7 and 8, each provided with

a chimney 9 of the usual construction, having several normally concentric cylindrical walls 10, surrounding the central flue 11. In Figure 1, the chimney has been removed from the position shown by dotted lines above the burner 7, and has been placed on the plate 12, which is constructed in accordance with my invention, and rests upon the grid 13.

The plate 12 is formed of upper and lower layers 14 and 15 stamped from thin sheet iron, or other suitable material, and the outer edge 16 of one of the plates is preferably folded over the other, so as to form a smooth periphery. Immediately underneath the upper layer 14 is a layer 17 of zinc, and between the latter and the lower layer 15 is a layer of asbestos 18. These several layers are secured together at the edges preferably by rivets 19. A handle 20 may be secured by one of the rivets. After these layers have been riveted together, a plurality of openings are punched therethrough to permit the flame from the burner beneath the plate to pass upwardly through the space between the walls 10. As shown in Figure 3, these openings preferably include a central opening 21, the shape of which is immaterial, and several series of concentric 85 arcuate slots 22, the location of which will be determined in accordance with the size and arrangement of the various passageways through the chimney.

The use of zinc in a furnace for the production of vapor which will clean the soot from the flues is well known, and in the present invention I preferably use zinc between the sheet iron layers 14 and 15, although this is not absolutely essential. The layer of asbestos is preferably used underneath the zinc, to prevent the latter from melting and running.

When the plate 12 is placed on the grid 13, it causes the flames from the burner beneath to spread outwardly and to heat the entire plate. The hot flames will pass upwardly through the openings 21 and 22, and consequently a chimney placed above the plate 12 will be subjected to an intense heat especially at the bottom portion where the oil, soot, grease and the like have accumulated. These accumulations will all be burned off in a few minutes, and the chimney will be as clean as when first bought.

As indicated in Figure 1, the preferred manner of using the invention is by placing

it above the griddle of one burner, while a chimney from one of the other burners is cleaned. Thus, each chimney may in turn be cleaned from one of the other burners. 5 It will be understood, however, that the invention may be utilized in other ways, the application of an intense heat to the plate 12 being the essential thing.

In the foregoing description I have described specifically the preferred structure, by means of which this method of cleaning chimneys is carried out, but it is to be understood that various changes may be made in the structure thereof, as well as in the manner of its application without departing from the principles of the invention as expressed in the appended claims.

What is claimed is:

1. A plate for cleaning an oil stove chimney, comprising two layers of sheet iron with a layer of asbestos and a superposed layer of zinc between the layers of sheet

iron, the whole being suitably secured together, and having a series of openings therethrough including a central opening, 25 and a series of arcuate slots arranged concentric to the central opening and of such radius that they will register with the respective flues of the chimney when the latter rests centrally on the plate. 30

2. A plate for cleaning an oil stove chimney, comprising upper and lower metallic layers with a sheet of asbestos and a superposed sheet of zinc between said metallic layers, all of said layers having a series of 35 openings therethrough which are so disposed that when the chimney is placed centrally upon the plate they will register with the respective flues through the chimney and permit the heat to pass therethrough. 40

In testimony, that I claim the foregoing as my own, I have hereto affixed my signature.

WILLIAM HANDLER.
